UNITED STATES PATENT OFFICE.

JAMES WILLIAM DAVIS AND SOLON MCGAW, OF FAYETTEVILLE, TENNESSEE.

TENON-CUTTER.

SPECIFICATION forming part of Letters Patent No. 650,827, dated June 5, 1900.

Application filed March 6, 1900. Serial No. 7,533. (No model.)

To all whom it may concern:

Be it known that we, JAMES WILLIAM DAVIS and SOLON MCGAW, citizens of the United States, residing at Fayetteville, in the county 5 of Lincoln and State of Tennessee, have invented a new and useful Bit and Bit Attachment for Hollow Augers and other Edged Tools, of which the following is a specification.

This invention relates to augers, and particularly to that class known as "hollow" augers; and the object of the same is to provide simple and effective means for applying and adjusting the bits in a positive manner and without requiring complex manipulation and 15 with a more accurate result, as well as equal inward extent of the cutting edges of the bits.

The invention consists in the construction and arrangement of the several parts, which will be more fully hereinafter described and 20 explained.

In the drawings, Figure 1 is a perspective view of an auger embodying the features of the invention. Fig. 2 is a front elevation of the improved auger. Fig. 3 is a section on the 25 line 3 3, Fig. 2. Fig. 4 is a detailed perspective view of the parts of the improved attachment.

Similar numerals of reference are employed to indicate corresponding parts in the several 30 views.

The numeral 1 designates a tubular body of ordinary form, having slots 2 at diametrically-opposite points for obvious reasons, and an angular extremity 3 for attachment to or 35 engagement by a holding or gripping device, the opposite end of the body 1 being provided with an extended head 4, having a flat face 5, with diametric slots 6 and a central opening 7, leading to the body 1. The face 5 provides a rest against which the work is placed, and is consequently made smooth or even and of sufficient extent as to practically serve its intended purpose. The inner or rear side of the head 4 has inclined seats 8, formed at 40 diagonally-opposite points therein, which are regularly inclined outwardly toward the face 5 and lead to the slots 6. In these seats 8 bits 9 are adjustably mounted and have their beveled cutting edges 10 exposed through the 45 slots 6 in the manner clearly illustrated by Fig. 2, and in consequence of the diagonal position of the seats 8 the beveled cutting

edges 10 of the bits will project beyond the reverse walls of the opposite slots 6. Each of the bits has a longitudinally-disposed slot 55 11 and a rear inturned angular end 12, having a centrally-slotted edge to provide a seat, as at 13. On the bit 9 a cap 14 is mounted and constructed with a screw-opening 15 to receive a holding-screw 16, adjustable in a 60 screw-opening 17 in an adjacent portion of the head 4 and extending through the slot 11. The cap 14 also has an inclined or inwardly-directed extremity 18 adjacent the inturned end 12 of the bit, and extending through the 65 said extremity 18 is a screw-opening 19 to adjustably receive the screw-shank 20 of an adjusting-screw 21, having a head 22 standing outwardly from the inturned end 12 of the bit and also provided with a collar 23 at a 70 distance from the forward extremity of said head to provide a circumferential groove 24, which acts in conjunction with the seat 13 in the said inturned end 12 of the bit. When the screw-shank 20 is located in the extremity 75 18 of the cap 14, a movement of the said bit either toward or away from the inturned end 18 of the cap may be acquired without changing the position of the head of the screw relatively to said inturned end of the bit in view 80 of the collar 23 and the groove 24. To obtain this adjustment, it will be understood that the screw 16 will remain in fixed position, the said bit being permitted to slide by reason of the provision of the slot 11. 85

The screw-heads 22 and the inturned ends 12 of the bits are located nearer the body 1 and wholly inward from the plane of the seats 8, and the said bits are thereby made easily adjustable, and a slight turning of the screw-head in either one or both will produce a quick response, as desired, at the beveled cutting ends 10 relatively to the walls of the slots 6, through which they project, and thus have the said cutting edges of the bits operate 95 either light or heavy.

It will be understood that the present form of auger is particularly intended for constructing tenons on the ends of pieces of material and that the latter are caused to bear against 100 the face 5 with sufficient pressure to have the cutting edges 10 carry on their work, and thereby gradually and regularly produce the tenon, the reduced portion of the device being

operated on passing into the body 1 through the opening 7, and the length of the tenon will depend upon the length of the body, as will be readily apparent, unless the work is removed previous to the reduced portion thereof of having its end strike the rear wall of the said hollow body.

The improved bit attachment has been shown applied to a hollow auger to illustrate one form of practical use of the same; but it will be understood that it is proposed to apply the same to any tool to which it may be adapted and wherein the holding-screw 16, serving to clamp the cap 14 or retain the latter in a fixed position and also permit the bit to move between the cap and the seat therefor, will be found beneficial and advantageous.

The improved bit-adjusting devices set forth possess manifold advantages and require less labor in obtaining a sensitive adjustment than other analogous devices heretofore used, and to suit various applications changes in the form, size, proportions, and minor details may be resorted to without departing from the principle or sacrificing any of the advantages of the invention.

Having thus described our invention, what we claim is—

1. In a hollow auger, the combination of a hollow body having a head, diametrically opposed slots, and inner inclined seats directed

toward the said slots, and bit attachments disposed on the said seats, and each consisting of a longitudinally-slotted bit with an inwardly and rearwardly extending outer end, 35 a cap mounted on the said bit, and also having its outer end directed inwardly parallel with the end of the bit and formed with a screw-aperture, an adjusting-screw having a circumferential groove portion engaging the in-turned end of the bit and its shank located in the screw-threaded aperture in the inturned end of the cap, and means for connecting the cap and the bit to the head.

2. A bit attachment for tools, comprising a 45 bit and a cap with inturned rear extremities, an adjusting-screw engaging said extremities and operating to move the bit, and a holding-screw extending through the cap and the bit into the support for said devices to hold the 50 cap in fixed clamping position, the bit being slotted longitudinally to permit the screw to pass therethrough and allow adjustment of the said bit.

In testimony that we claim the foregoing as 55 our own we have hereto affixed our signatures in the presence of two witnesses.

JAMES WILLIAM DAVIS.
SOLON McGAW.
